CLAIM

The ornamental design for a photographic close up
setting apparatus, as shown and described.

DESCRIPTION

FIG. 1 is a perspective view of the photographic close
up setting apparatus from the front and one side showing
our new design;

FIG. 2 is a perspective view of the apparatus from the
front and other side;

FIG. 3 is a rear elevation thereof; and

FIG. 4 is a bottom plan view thereof.

FIG. 1

FIG. 2

FIG. 3

FIG. 4
